UNITED STATES PATENT OFFICE.

THEOPHILE REVILLÉ, OF PARIS, FRANCE, ASSIGNOR TO GASTON FERNAND CLAUDE JOLY, OF PARIS, FRANCE.

IGNITION SPARK-GAP DEVICE.

Application filed May 22, 1922. Serial No. 562,909.

To all whom it may concern:

Be it known that I, THEOPHILE REVILLÉ, a citizen of the French Republic, residing at 17, rue des Acacias, Paris, France, have invented certain new and useful Improvements in Ignition Spark-Gap Devices, of which the following is a specification.

This invention relates to ignition spark-gap devices for internal combustion engines.

10 Numerous spark-gap devices or spark-intensifiers are now used for internal combustion engines; none of these devices is completely adjustable, that is to say, none of them allows the progressive increase of the 15 spark-gap, starting from actual closed contact and with fixation at the selected distance for ignition, without any interruption of the current.

The present invention obviates this defect 20 by means of a device which provides, without interruption of the current and as desired, either continuity of the current by contact of the electrodes, or interruption at the gap with variable intensity by regular and 25 progressive increase of the distance between the electrodes with fixation at any degree of spark-gap effect.

This device placed in the electric ignition circuit is essentially characterized by two insulating bodies screwing into one another, 30 each of them being traversed by an electrode of which the axis coincides with the axis of the screw-threads on the insulating body; one of the electrodes is rigidly fixed in its 35 seating and its inner end terminates in line with a ventilating hole formed transversely in the insulating body. The second electrode, provided at its outer end with a terminal for the wire, can revolve in the insulating body which encloses it with a small 40 amount of play, which allows the screwing and unscrewing of the body which supports it, upon the other, that is to say, the progressive approach or separation of the electrodes, without it being necessary for this 45 purpose to detach the wire, that is to say, to break the circuit.

The description hereafter given with reference to the annexed drawing, by way of 50 example, will facilitate the understanding of the invention realized.

Figure 1 is a vertical section of the arrangement showing the electrodes in contact.

Figure 2 shows the same, in part section 55 on a plane at right angles, the electrodes being separated apart from one another.

Figure 3 is a plan view of a detail hereafter described.

Figure 4 shows the apparatus mounted on 60 a spark plug.

The mounting made of insulating material, is composed of two principal parts *a* and *b* screw-threaded one into the other; both are traversed by a passage serving as a 65 location for the two electrodes, the one *c* screwed into the part *a*, the other *d* held with slight friction in the part *b* within which it can be rotated. The latter electrode, bored at its lower part to provide a 70 hole *e* serving to receive the high-tension cable which is secured by the set-screw *f*, is maintained in its location on one side by a circular collar *g* bearing against a flange *b'* formed in the part *b* and on the other side by 75 a split or spring ring *h* seated in a groove formed around the electrode *d* and bearing against the lower end of the part *b*. The point *c'* of the fixed electrode *c* is visible 80 at the vent-hole *i*. An accessory sleeve *j* made of insulating material, screwed to the bottom of the body *b* serves as a cable-shield.

When the mounting *b* is screwed up on the body *a* (as shown in Figure 1), the 85 points *c'* *d'* of the two electrodes are in contact and ignition takes place by direct conduction. On the other hand, in proportion as the mounting *b* is unscrewed, the points 90 of the electrodes separate to form an external spark-gap (as shown in Figure 2).

The electrode opposite to the high-tension cable-attachment may end in a ring or eye *k* permitting the direct fixation of the device upon the spark plug *l* (as shown in 95 Figure 4).

The shapes and accessory arrangements of the various parts of the device described, their dimensions and constituent materials, the adjustment of the electrodes in the insulating mounting, and the means for fixation of the device upon the sparking plug or in the electric circuit, can be varied without departing from the present invention. It will be understood that modifications, 100 additions and improvements, within the scope of the invention, can be made in the device described.

Having thus described my invention, what I claim is:—

1. An ignition spark gap device, comprising a pair of axially alined electrodes, spark 5 points at the adjacent extremities of said electrodes, insulating supports for said electrodes, said insulating supports having a screw connection with one another and being coaxial with said electrodes, one of said 10 electrodes fixed rigidly in its support and having its pointed extremity in line with a vent hole formed transversely in said support, an attachment ring at the outer extremity of said electrode, the other of said 15 electrodes being revoluble in its support, a collar upon said revoluble electrode, a hollow outer extremity to said revoluble electrode, a ring encircling said outer extremity, said collar and ring bearing against said 20 insulating support of said revoluble electrode, means for securing a cable end in said

hollow extremity, and a cable shield of insulating material screwed upon the outer extremity of the insulating support of said revoluble electrode.

25

2. An ignition spark-gap device, comprising two insulating bodies, said bodies screwing one into the other, an electrode fixed rigidly in one of said bodies, an electrode mounted revolubly in the other of said 30 bodies, said electrodes being alined and having their adjacent ends in proximity to a vent opening in one of said bodies, means for preventing longitudinal movement of the revoluble electrode in its supporting body, 35 means for attaching said fixed electrode to a spark plug, and means for connecting a conductor to said revoluble electrode.

In testimony whereof I hereunto affix my signature.

THEOPHILE REVILLÉ.
